CLAIM

The ornamental design for a sports bag, as shown and described.

DESCRIPTION

FIG. 1 is a front perspective view of a sports bag, showing my new design with items inserted into open pockets;

FIG. 2 is a rear perspective view thereof;

FIG. 3 is a front perspective view thereof, illustrated without the items and with the pockets closed;

FIG. 4 is a rear perspective view of FIG. 3;

FIG. 5 is a front elevational view of FIG. 3;

FIG. 6 is a rear elevational view of FIG. 3;

FIG. 7 is a left-side elevational view of FIG. 3;

FIG. 8 is a right-side elevational view of FIG. 3;

FIG. 9 is a top plan view of FIG. 3; and,

FIG. 10 is a bottom plan view of FIG. 3.

The broken lines in the figures depicting items held within pockets of the design form no part of the claimed design. The remaining broken lines depict stitching, and do form part of the claimed design.
